UNITED STATES PATENT OFFICE

ALPHEUS H. TENNENT, OF CLEVELAND, OHIO, ASSIGNOR TO THE OIL CONSERVATION ENGINEERING COMPANY, OF CLEVELAND, OHIO, A CORPORATION OF OHIO

DISTILLING APPARATUS FOR USE IN RECLAMING OILS

Application filed October 8, 1928. Serial No. 311,045.

The present invention relates to an evaporator for oil and more particularly to an evaporator for removal of the diluents of crank case oils and the like which are to be reclaimed. Such oils have free carbon and other impurities which tend to settle out during heating and the carbon particularly tends to cake on the heated portions of the still. To prevent such caking and consequent heating losses and to obtain circulation and movement of the oil during the heating process, the present evaporator uses a series of cartridge type heaters with spaced enclosing tubes through which the oil will circulate and thus prevent the deposit of carbon and the like. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

Fig. 1 is a vertical longitudinal section through the still; and Fig. 2 is an end elevation.

The present evaporator provides a chamber 1 with a series of cored bosses 2 extending upwardly into the chamber from the bottom and preferably spaced along the center line of the chamber. The walls 3 of the chamber are higher than the bosses and have a trough member 30 to receive any overflow due to foaming, there being a series of return apertures 31. The trough member 30 terminates in a horizontal flange 4 with a downturned lip 5.

The hood or condenser portion consists of a collecting member 7 having its short side 8 mounted against the underside of the flange 4 with an asbestos or insulating packing 9 therebetween, the low portion having an outlet 10 to a storage tank (not shown) for the condensed products. To the long side 10 of the collecting member is attached the condensing hood 12. The sides of the evaporator

chamber are covered with a suitable insulating packing to hold the heat, the bottom wall being extended as at 32 to provide a support for the covering.

The cored bosses 2 are interiorly threaded 55 at the bottom as at 15 and are adapted to receive removably mounted cartridge type electric heating elements 16 which are held in place by nipples 17 screwed into the bosses, the connecting wires 18 passing out through the nipples and being connected to the usual control box.

To obtain continuous oil circulation during the heating operation, each boss is surrounded by a spaced tube 20 which is supported 60 on a series of lugs 21 formed integrally with the bosses near the bottom. These tubes form cylindrical chambers around the heating bosses and are maintained in their spaced relation by spaced lugs 33 formed on the bosses and thus the oil passes up through these chambers, keeping and maintaining a constant circulation past the heating elements. This circulation not only aids in the distillation of the diluents but also substantially eliminates the deposit of carbon on the heating bosses and cylinders.

The present apparatus provides a rapid heating and distillation of the diluents from crank case and similar oils and also provides a distilling chamber or evaporator which can easily be cleaned. The cylinders are easily removable and thus the bosses as well as the cylinders can be readily cleaned. By the use of removable cartridge type heating elements, replacement of these elements may be quickly and easily accomplished without disturbing the apparatus as a whole. Heat control is easily obtained by varying the current through the elements. The hood and condenser construction are such as to make assembly and dismantling, if necessary, easy and inexpensive and the entire construction provides an economical, rapidly operating unit particularly adapted to use with dirty 85 oils of the crank case type.

Other modes of applying the principle of the invention may be employed instead of the one explained, change being made as regards the mechanism herein disclosed, provided the 95 100

means stated by any of the following claims or the equivalent of such stated means be employed.

I therefore particularly point out and distinctly claim as my invention:—

1. An evaporator for oils consisting of an open chamber having a horizontal top flange with a down-turned lip, a series of spaced cylindrical bosses formed integrally with said chamber and extending upwardly from the bottom, said bosses being hollowed out from the bottom, heating elements removably mounted in said bosses, cylindrical tubes mounted around said bosses and spaced therefrom and from the bottom of said chamber, a condensate collecting member secured to the under side of said horizontal flange, and a condenser hood secured to said collecting member.
2. An evaporator for oils consisting of an open chamber having a horizontal top flange with a down-turned lip, a series of spaced cylindrical bosses formed integrally with said chamber and extending upwardly from the bottom, said bosses being provided near the bottom with a series of spaced radially extending lugs and having spacing lugs thereabove, heating elements mounted in said bosses, cylindrical tubes mounted around said bosses and spaced therefrom, said tubes resting on said bottom lugs and being held in spaced from said bosses by said other lugs, a condensate collecting member secured to the under side of said horizontal flange, and a condenser hood secured to said collecting member.

Signed by me this 1st day of October, 1928.

ALPHEUS H. TENNENT.
